(57) CLAIM

The ornamental design for a hand phone case, as shown and described.

DESCRIPTION

FIG. 1 is a front perspective view of a hand phone case showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly segmented broken lines indicate unclaimed portions of the article that form no part of the claimed design. The dot-dash broken lines represent the claim boundary that forms no part of the claimed design.

1 Claim, 6 Drawing Sheets
